CLAIM

The ornamental design for a cosmetic bag, as shown and described.

DESCRIPTION

FIG. 1 is a front, left and top perspective view of a cosmetic bag, showing my new design;

FIG. 2 is a perspective view in the disassembled configuration thereof;

FIG. 3 is another perspective view in the further disassembled configuration thereof;

FIG. 4 is a front view of FIG. 1;

FIG. 5 is a rear view of FIG. 1;

FIG. 6 is a left side view of FIG. 1;

FIG. 7 is a right side view of FIG. 1;

FIG. 8 is a top view of FIG. 1; and,

FIG. 9 is a bottom view of FIG. 1.

The broken lines shown in the drawings illustrate portions of the cosmetic bag that form no part of the claimed design.

1 Claim, 9 Drawing Sheets
